UNITED STATES PATENT OFFICE.

GRANT H. SHANNON, OF SAN FRANCISCO, CALIFORNIA.

CLOTHES-WASHER.

1,332,858.

Specification of Letters Patent. Patented Mar. 2, 1920.

Application filed March 30, 1917. Serial No. 158,560.

To all whom it may concern:

Be it known that I, GRANT H. SHANNON, a citizen of the United States, and a resident of the city and county of San Francisco, State of California, have made a new and useful invention, to wit: Improvements in Clothes-Washers; and I do hereby declare the following to be a full, clear, concise, and exact description of the same.

10 The invention relates particularly to percolating clothes washers in which the steam pressure expansion of the water in the bottom of the boiler elevates the water above the clothes contained in the boiler, through 15 which it percolates with cleansing effect.

Among the objects of the invention are to provide a simple and efficient washer of this type easily constructed and manipulated, combined and arranged to operate 20 most effectively.

In this specification and the annexed drawings, the invention is illustrated in the form considered by me to be the best, but it is to be understood that the invention is 25 not limited to such form, because it may be embodied in other forms, and it is also to be understood that in and by the claim following the description, it is desired to cover the invention in whatever form it may be 30 embodied.

In the accompanying one sheet of drawings:

Figure 1 is a side view of a clothes washer in perspective, constructed in accordance 35 with this invention, a portion of the boiler being broken away to disclose the interrelation of parts.

Fig. 2 is a plan view from beneath of the spray manifold of the percolator.

40 Fig. 3 is a fragmentary detail view of the locking mechanism of the clothes retaining grid.

The principle involved in washing clothes in water is dissolving and carrying the dirt 45 from the fabric by forcing water through the fabric. This is variously accomplished, either in the primitive manner of pounding the clothes on a rock with a club or the more modern way of rubbing on a wash 50 board, or by means of machinery utilizing cylindrical washers with suitable agitators for forcing the cleansing solution through the fabric. These various methods of cleaning are more or less effective, the hand 55 method being inefficient and the mechanical method resulting in excessive wear and tear

on the fabric, with the added disadvantage that the cleansing solution is kept in constant agitation, the dirt or soilure removed from the fabric having no opportunity to 60 settle, and to gain time and to dislodge the stains resulting from a discolored washing solution, chemicals are resorted to, all of which are deleterious to the fabric being 65 washed.

In the present invention the mechanical process is reversed by holding the clothes or fabric *en masse* and circulating the cleansing solution therethrough, separating the soilure removed from the fabric from the 70 solution, whereby a relatively clear solution is always circulating or being passed through the fabric. Because of the separation of the dirt from the solution the fabrics are not discolored thereby and the necessity for bleaching and caustic elements 75 is obviated.

In detail the construction illustrated in the drawings includes a conventional wash boiler 1 of any desired shape, having a removable cover 2 fitted thereto. Into this boiler is removably fitted a false bottom 3 having the depending flange 4 around the edge resting on the bottom of the boiler and raising the false bottom the desired distance 80 above the bottom of the boiler, the false bottom being of such dimension that the flange 4 rests away from the wall of the boiler 1, providing a space between said flange and the boiler wall. The false bottom and its flange resting on the bottom of the boiler provide a receptacle separate 85 from the boiler proper for the generation of steam. The conical tubular risers 5 and 6 are hermetically fixed in openings in the 90 false bottom 3, preferably at opposite ends of the boiler. The upper ends of these tapered risers fit into the tapered elbows 7 and 8, leading into the spray chambers 9 and 10 respectively. These spray chambers 95 extent across the greater portion of the length and breadth of the boiler, and preferably are divided longitudinally into two distinct spray chambers as indicated in Fig. 2, this form being found to accomplish a 100 better distribution of the water than if both discharges 7 and 8 led into a single spray 105 chamber.

The openings indicated in the spray chamber in Fig. 2 for better illustration, are out 110 of proportion to their actual size, being in actual practice of less area than the size in-

dicated in Fig. 2 and about five hundred in number for the conventional domestic boiler.

The grid frame 12 is supplied with a pivot 13 adapted to engage holes in the bracket 14 fixed to one of the risers 6, the opposite end of the grid provided with a slidable pivot 15 engaging holes in the bracket 15' fixed to the riser on the opposite side, the bolt being guided by the plate 17 fixed thereto and having holes engaging the grid bars 18—18. The holes in the brackets 14 and 15' provide vertical adjustment for the grid 12 for the purpose of clamping the clothes between the grid and the false bottom 3.

15 This washer operates substantially as follows:

The clothes or fabric to be washed are placed in the boiler on top of the false bottom 3 and clamped in position by the grid 12, sufficient water is then placed within the boiler to more than cover the false bottom 3. The boiler is then set on the stove and the temperature of the water raised and maintained at boiling point. The steam generated beneath the false bottom 3 forces the water up the risers 5 and 6 and into the spray chambers 9 and 10 from which it sprays back on top of the clothes beneath the grid 12, percolating therethrough and dislodging any soilure therein. The water is fortified by any suitable neutral soap—strong soap being unnecessary—to increase the cleansing effect. The excess of steam pressure beneath the false bottom 3 escapes therefrom through the openings 19 distributed throughout the area of the false bottom. The scalding steam forcing its way up through the fabric, thoroughly cleanses and sterilizes the fabric and coöperating with the water that is percolating therethrough accomplishes the desired effect.

Practice has demonstrated that 30 to 35 minutes of this boiling, steaming and percolating operation is sufficient to accomplish

entire cleansing of ordinary household laundry, without the necessity for rubbing or the use of cleansing chemicals other than mild soap, the saving in wear and tear on the fabric due to mechanical operations or rubbing is sufficiently manifest. Practice has proven that dirt and foreign matter dislodged from the clothes settles in the bottom of the boiler between the walls thereof and the flange 4, and on the bottom of the boiler between it and the false bottom 3. Since the horizontal cross-section of the risers 5 and 6 decreases from their bottoms to their tops, the rate of upward flow must increase and this increased rate of flow will thus precipitate any dirt or foreign matter suspended therein.

To relieve any excessive steam pressure in the boiler I provide the ventilator 20 in the lid 2. The ventilator is slidable between the guides 21—21 by means of a convenient handle 22, and is provided with the openings 23 registering with the openings 25 provided in the cover 2.

Having thus described this invention, what I claim and desire to secure by Letters Patent is:

In a clothes washer, a boiler; a perforated false bottom spaced above the bottom of said boiler and having a depending flange spaced laterally from the sides of said boiler; independent spray chambers arranged parallel longitudinally near the top of said boiler on opposite sides of the center thereof; risers at opposite ends of said false bottom and communicating with the space beneath same and connected at their tops with the opposite ends of said spray chambers respectively.

In testimony whereof I have hereunto set my hand at San Francisco, California, this 24th day of March, 1917.

GRANT H. SHANNON.

In presence of—

A. J. HENRY.
